UNITED STATES PATENT OFFICE.

DAVID GERBER, OF BALTIMORE, MARYLAND, ASSIGNOR TO MARYLAND BAKING COMPANY, OF BALTIMORE, MARYLAND, A COPARTNERSHIP COMPOSED OF JOSEPH SHAPIRO, ISAAC SHAPIRO, NATHAN SHAPIRO, AND SAMUEL SHAPIRO.

DESIGN FOR AN ICE-CREAM CONE.

Application filed August 28, 1923. Serial No. 7,113. Term of patent 14 years.

To all whom it may concern:

Be it known that I, DAVID GERBER, a citizen of the United States, residing at Baltimore, in the State of Maryland, have invented a new, original, and ornamental Design for Ice-Cream Cones, of which the following is a specification, reference being had to the accompanying drawing, forming part thereof.

The figure is a perspective view of an ice cream cone, showing my new design.

I claim:

The ornamental design for an ice cream cone, as shown.

DAVID GERBER.
